UNITED STATES PATENT OFFICE.

JOSEPH T. BOUFFORD, OF LINWOOD, MASSACHUSETTS.

SCRAPER.

SPECIFICATION forming part of Letters Patent No. 629,487, dated July 25, 1899.

Application filed May 18, 1899. Serial No. 717,319. (No model.)

To all whom it may concern:

Be it known that I, JOSEPH T. BOUFFORD, of Linwood, in the county of Worcester and State of Massachusetts, have invented a new and useful Improvement in Scrapers; and I hereby declare that the following is a full, clear, and exact description of the same, reference being had to the accompanying drawings, forming part of this specification.

10 This invention has reference to an improvement in a tool designed for use in smoothing and scraping the surfaces of floors and other woodwork; and it consists in the peculiar and novel construction of the scraper, as will be 15 more fully set forth hereinafter.

When woodwork, and particularly hard wood, has been brought to the desired surface and is designed to be varnished, waxed, or polished, the marks of the plane are 20 moved by a steel plate, usually held by the hands of the user.

In finishing the surfaces of floors and other woodwork the scraping with the usual steel plate is very fatiguing.

25 To facilitate the use of the scraper is the object of this invention.

Figure 1 is a side view of my improved scraper. Fig. 2 is a top view, and Fig. 3 an end view, of the same. Fig. 4 is a front view 30 of the scraper-plate, and Fig. 5 is a sectional view of the scraper.

In the drawings, A indicates a preferably rectangular bar having the handle a at one end and the bevel end a' at the opposite end. 35 Near the lower edge of the bevel end a' the pins a² are secured in the bar A so as to project slightly above the surface and enter the slot b³ to prevent the side movement of the plate B.

40 The plate B is a thin steel plate having at one end the straight scraping edge b' and at the other end the curved edge b². The plate also has the slot b³, having at its opposite ends a width equal to the shank of the screw b⁴ and in the center an enlarged opening, through 45 which the head of the screw b⁴ may be passed. The plate C, which is slightly tapering and of wedge-shaped section, as is shown in Figs. 1 and 5, is provided with the central slot c', the lower end of which is enlarged, so that 50 the head of the screw b⁴ can readily pass through, the other portion of the slot c' being of a width sufficient for the passage of the shank of the screw b⁴. The upper end of the

plate B is provided with the handhold c², of 55 convex form, adapted to fit the ball of the hand.

In assembling the parts the screw b⁴ is secured in the beveled end of the bar A. The plate B is placed over the head of the screw 60 b⁴ and adjusted to bring the contracted portion of the slot b³ to bear on the shank of the screw, the pins a² entering the lower contracted portion of the slot b³. The holding-plate C is placed over the head of the screw 65 b⁴ and pushed down to wedge the same between the head of the screw b⁴ and the plate B, and by so doing holds it firmly against the beveled end a' of the bar A, the screw b⁴ and the pins a² holding the plate B against side 70 movement.

In use the handle a of the bar A is grasped by one hand and the ball of the other hand is pressed on the handhold c². Usually the curved edge b² is used first to rough-scrape, 75 and then the plate B is reversed, so as to finish with the straight edge b'. When used on floors, the operative by slightly stooping can draw the scraper over the floor and readily scrape the same. The spring of the steel plate 80 B materially facilitates the operation.

Having thus described my invention, I claim as new and desire to secure by Letters Patent—

1. In a tool of the nature herein described, 85 the combination with a bar having at one end the handle a and at the other end the beveled end a', of a screw b⁴, the slotted, spring-steel plate B, the curved edge b² and the straight edge b' at the opposite ends of the plate, the holding-plate C of wedge-shaped section and 90 the handhold c² at one end of the plate, as described.

2. In a scraping-tool, the combination with the bar A having the handle a at one end and 95 the beveled end a' at the opposite end, of the slotted, spring-steel plate B, the pins a² on the beveled end of the bar A, the holding-plate C, the handhold c² on the same and the screw b⁴; whereby the spring of the steel scraper is increased, as described. 100

In witness whereof I have hereunto set my hand.

JOSEPH T. BOUFFORD.
